UNITED STATES PATENT OFFICE

GEORGE F. LEWIS, OF MONTCLAIR, NEW JERSEY, ASSIGNOR TO FOOTE, PIERSON & COMPANY, INC., OF NEW YORK, N. Y., A CORPORATION OF NEW YORK

FURNITURE REST OR SHOE

Application filed May 18, 1929. Serial No. 364,025.

The present invention relates to an improved furniture rest or shoe and constitutes an improvement upon the construction disclosed in my U. S. Patent #1,658,244, dated Feb. 7, 1928.

In the construction shown in said patent a base member is provided with a socket opening in which a headed pin is rockably mounted, this pin being in the form of a pair of legs which are bowed outwardly along their full length and are adapted to frictionally engage within a hole in a furniture leg.

In the present improvements I propose to provide a pin having two legs which are bent outwardly at two spaced points in opposed relation to form lateral enlargements, one of these points being adjacent the base, whereby it has the function of retaining the base in relation to the head of the pin, while the other is at the upper end of the pin and has the function of interlocking with the grip-neck socket into which the pin is adapted to be inserted, and whereby the pin and base are connected to the socket. The lower enlargement is further adapted to frictionally grip within the socket to resist relative pulling and turning movement of the pin therein, while the two enlargements cooperate to position the pin axially within the socket and resist the twisting strain exerted thereon during tilting of the base.

It is also an object to provide such a pin which may be inserted directly in a drilled hole in the furniture leg, and in which there is no socket employed, and which will effectively retain the device in place.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a side elevation of a furniture rest or shoe, according to the present embodiment of the invention;

Fig. 2 is a perspective view of the grip neck socket employed therewith;

Fig. 3 is a plan view of the rest;

Fig. 4 is a vertical sectional view showing the same mounted within the socket in a furniture leg;

Fig. 5 is a similar view, and showing a tilted position of the device;

Fig. 6 is an elevation of the pin employed, and in its condition before assembly with the base;

Fig. 7 is a cross sectional view thereof, taken along the line 7—7 of Fig. 6; and

Fig. 8 is a view partly in section, showing the device as inserted in a hole in a furniture leg, and without employing the grip-neck socket.

Similar reference characters indicate corresponding parts throughout the several figures of the drawings.

Referring to the drawings, the furniture rest or shoe, according to the present embodiment of the invention, comprises a base 10, preferably solid and formed of bakelite or other suitable material, having a flat floor-engaging bottom surface 11 and an upper surface in the shape of a spherical dome 12, annularly shouldered at 13. A central opening 14 extends vertically through the base, being restricted, as at 15, to provide an annular shoulder, and being flared outwardly above said shoulder, as at 16. The dome 12 is of a suitable radius to provide a curved seat 18 for the tilting part of the device, and also to provide ample material to resist crushing stresses between the upper surface and the wall of the opening 14.

A centrally apertured washer 17, preferably used, rests on the domed portion 12 of the base, and is shaped to conform thereto, the edge of the washer being normally spaced above the shoulder 13, so that the washer is free to slide in all directions upon the dome.

The pin, indicated generally as 18, is preferably a split pin, formed by bending wire of substantially semi-circular cross-section upon itself, a substantially circular eye or head 19 being formed at the bight, so that the pin, as shown in Fig. 6 before assembly with the base, has the appearance of a cotter pin. The head 19 is of such size that it will fit loosely within the opening 14 of the base and have rocking abutment against the shoulder 16.

15, while the stem formed by the two legs may have free gyratory movement within the flared portion 16 of the opening. The pin is assembled upwardly through the aperture of 5 the washer 17, this aperture fitting snugly about the two legs. The two legs of the pin are bent or spread outwardly just above the washer, as at 20, forming a lateral enlargement which retains the base and washer in 10 relation to the head 19, and further provides a bottom bearing and retaining means within the socket, as will presently more fully appear. The pin is also bent or spread at its upper end, as at 21, in axially spaced relation 15 to the enlargement 20, the lateral enlargement formed by the bends 21 being of substantially the same projection with respect to the axis of the pin as the enlargement 20. The upper extremities of the pin are bent inwardly toward each other but are spaced apart to permit of inward compression of the two legs, the straight portions of the two legs being also spaced apart for this purpose, as clearly indicated in Fig. 1.

25 The socket with which the device is employed is preferably of the grip-neck type, and consists of a cylindrical tube 22, having a bottom disk 23 secured thereto in the usual manner, and adapted to be secured to the 30 furniture leg, as by means of the peripheral teeth 24, when the leg is of wood or other material into which the teeth may be driven. The upper portion of the tube is split longitudinally at suitable points, as at 25, and said upper 35 portion is tapered inwardly, thereby forming a springy upper portion and a restricted opening at the upper end. The drilled hole 26 in the furniture leg 27, into which the socket is engaged, extends substantially above the 40 upper end of the socket, as clearly indicated in Fig. 4.

The device is assembled in the socket by 45 pressing the same into place, the enlargement 21 at the upper end of the pin being compressed by the tapered portion of the socket, so that it forms a substantially rigid wedge-like head which, upon further inward pressure, spreads the spring portions of the socket, permitting the enlargement to pass through 50 the upper end of the socket. The spring portions then spring back to their normal position forming a restricting abutment below the enlargement 21, which prevents separation of the shoe from the socket, except by employing 55 considerable outward pull. The lower enlargement 20, in the meantime, is engaged within the lower end of the socket, being slightly compressed, so that the outward spring pressure of the pin is exerted against 60 the socket and serves to frictionally retain the pin within the socket against axial movement and also against relative turning. In 65 the fully engaged relation it will be seen that the enlargement 21 is out of tight engagement with the upper end of the socket, so that the

legs of the pin are free to exert their outward pressure, and thus permit the enlargement 20 to frictionally bear upon the socket wall with the full spring pressure of the pin. The two enlargements furthermore cooperate to retain 70 the substantial axial alignment of the pin against twisting strains exerted during the tilting action.

Fig. 5 shows a tilted position, it being understood that the leg may be tilted in any 75 direction while the shoe maintains a firm flat engagement with the floor.

In Fig. 8 I have shown the device inserted in a hole 28 in the leg, without employing the grip-neck socket. The pin is compressed and 80 through its spring pressure the enlargements have a binding frictional engagement within the hole, effectually retaining the pin against axial, turning, and twisting strains.

I have illustrated and described a preferred 85 and satisfactory embodiment of my invention, but it will be obvious that changes may be made therein, within the spirit and scope thereof, as defined in the appended claims.

Having thus described my invention, what 90 I claim and desire to secure by Letters Patent is:

1. In a retainer for a furniture support a split pin connected at its lower end to the support, and comprising two normally spaced resilient leg portions extended upwardly from said support and bent outwardly in opposed directions near their upper ends in angular relation to said leg portions to form shouldered lateral projections. 95

2. In a retainer for a furniture support a split pin connected at its lower end to the support, and comprising two normally spaced resilient leg portions extended upwardly from said support and bent outwardly in opposed directions near their upper ends in angular relation to said leg portions to form shouldered lateral projections, and being 100 bent inwardly toward each other above said outwardly bent portions.

3. In combination with a tubular socket adapted to be inserted in a furniture leg, a furniture support and a retainer therefor comprising a split pin connected at its lower end to said support and comprising two normally spaced resilient leg portions extended upwardly from said support and bent outwardly in opposed directions near their upper ends in angular relation to the lower portion thereof to form shouldered lateral projections, movable inwardly and outwardly as the leg portions are flexed and adapted to engage the tubular socket at the upper end thereof to thereby retain said support with respect to said tubular socket. 115

4. In combination with a tubular socket comprising inwardly projected retaining means and adapted to be inserted in a furniture leg, a furniture support and a retainer therefor comprising two normally spaced 120

resilient leg portions extended upwardly from said support and bent outwardly in opposed directions at a point below their upper ends in angular relation to the lower portion thereof to form shouldered lateral projections, movable inwardly and outwardly as the leg portions are flexed and adapted to engage above said inwardly projected retaining means of the tubular socket to thereby retain said support with respect to said tubular socket.

Signed at 160 Duane Street, New York, New York, U. S. A., this 7th day of May 1929.

GEORGE F. LEWIS.
